ATTORNEY

UNITED STATES PATENT OFFICE.

ADRIAN D. ADRIANCE, OF BROOKLYN, NEW YORK.

TOY ARROW.

1,423,551.

Specification of Letters Patent. Patented July 25, 1922.

Application filed April 6, 1921, Serial No. 459,094. Renewed June 9, 1922. Serial No. 567,234.

To all whom it may concern:

Be it known that I, ADRIAN D. ADRIANCE, citizen of the United States, and resident of Brooklyn, in the county of Queens and State 5 of New York, have invented a certain new and useful Toy Arrow, of which the following is a specification.

This invention relates to arrows for spring or air guns, spring bows, or bow guns, or in 10 an enlarged form can constitute a toy spear or hand arrow.

The object is to present a toy arrow, composed of the fewest number of parts, and provided with a safety pneumatic flexible 15 tip that will make the use of the arrow in and about the home, or against the bodies of others than the user, if struck thereby, harmless and free from shock,—that is to say, that the forward force of the arrow is absorbed by the flexible air filled tip of sufficient area to so cushion the blow as to remove all dangerous and undesirable results.

A further object is to provide a novel and simple means of attaching the pneumatic tip 20 or nipple firmly to the shaft of the arrow.

A further object is to furnish a novel means of imprisoning the air in the flexible tip by means of inserting in the neck of the elastic nipple and securely fastening therein 25 the shaft of the arrow.

Fig. 1 is a longitudinal section of one form of my invention.

Fig. 2 is a similar view of another form 30 and

Fig. 3 is a similar view of a third form.

Fig. 4 is an elevation of one form of the forward end of the arrow shaft.

Figs. 5, 6 and 7 show three forms of the rear end of the arrow shaft.

40 In Fig. 1 letter *a*, is a flexible envelope of the nipple; letter *b*, is the shaft of the arrow; letter *d*, is the chamber containing the imprisoned air; letter *e*, is the contracted neck of the nipple firmly gripping the shaft 45 of the arrow; letter *f*, is an enlarged flange running around the end of the nipple to furnish strength to same and to further grip the shaft; letter *j*, are the grooves furnished for the purpose of retaining a cohesive ce-

50 ment, used to better secure the nipple to the shaft, and to furnish means of imprisoning the air; letter *g*, indicates a film of cohesive cement on the inside neck of the nipple, and filling the said grooves, *j*, of shaft; letter *c*, 55 is the presumed point of contact when arrow strikes against an object.

In Fig. 2 letter *a*, is a more or less spherical flexible envelope of the tip; letter *b*, is the shaft of the arrow; letter *d*, is the chamber containing the imprisoned air; letter *e*, 60 is the contracted hollow neck of the tip firmly gripping the shaft of the arrow; letter *f*, is an enlarged flange running around the end of the neck to furnish strength to same and to further grip the shaft; letter *g*, 65 indicates a film of cohesive cement on the inside of the neck of the tip, securing the tip to the shaft; letter *i*, is a wall of the same flexible material and part of the envelope of the tip, thus making this style of 70 tip a more or less spherical chamber containing air with a concentric hollow or tubular neck projecting therefrom.

In Fig. 3 letter *a*, is a more or less spherical, flexible envelope of the tip; letter *b*, is the shaft of the arrow; letter *d*, is the chamber containing the imprisoned air; letter *h*, 75 is a solid tip projecting concentrically outward, and of the same material as the envelope of tip, and is used to fasten the tip in a hollow in the end of shaft; letter *g*, and letter *i*, corresponds with the contraction and the wall as in Figure 2.

Figure 4, is a side elevation of the end of the shaft secured in the nipple of Figure 1; 80 letter *j*, is a multiple of grooves of any desired shape, provided to furnish means to retain the fastening cement used to better secure the nipple in place, and to imprison the air.

Figures 5, 6, and 7 show three styles of rear end of shaft; letters *k* and *l*, show styles used in air or spring guns; letter *m*, shows style with groove used in spring bow or bow gun.

95 I do not limit my invention to any particular style or shape of a pneumatic tip, or to any form or method of securing same to shaft, the essential features being that the tips should be flexible and filled with imprisoned air.

100 Further, I do not limit my invention to the use of any special material, or to any style or shape of the shaft for the arrow, or to the shape of either end of same, as different uses will demand different forms.

Having now explained the nature of and described fully my invention, what I claim as new, and desire to secure by Letters Patent, is,—

110 A toy arrow comprising a flexible tubular, air filled tip, having an enlarged closed

end and a contracted open end, a shaft having a grooved end firmly inserted in said contracted end and gripped thereby, and cement to fill said grooves, to assist in fastening said nipple to said shaft and to seal in the air.

Signed at Brooklyn Borough, city of New

York, in the county of Queens and State of New York, this fourth day of April, A. D. 1921.

ADRIAN D. ADRIANCE.
